UNITED STATES PATENT OFFICE.

GEORGE S. SEARLE, OF ROCHESTER, NEW YORK

STREET-INDICATING DEVICE.

Application filed August 25, 1926. Serial No. 131,501.

The present invention relates to a street indicating device and has for its object to provide improved means for use at street or highway intersections adapted to display the names or numbers of the streets or other signs useful in assisting pedestrians and motorists to find their way.

A further object of the invention is to provide an improved street sign of simple construction adapted for quick and ready attachment to lamp posts and the like which is so designed and placed as to be effectively illuminated by the ordinary street lamps whereby to display the names or numbers of cross or intersecting streets regardless of the angle of their intersection.

A further object of the invention is to provide an improved bracket for attachment to a lamp post or other support adapted to permit name plates for intersecting streets to be quickly applied thereto and being so constructed as to display the name plates in a manner to be effectively illuminated by a lamp carried by the post.

To these and other ends the invention resides in certain improvements and combinations of parts, all as will be hereinafter more fully described, the novel features being pointed out in the claims at the end of the specification.

In the drawings:—

Figure 1 is a front elevation of a device embodying one form of the invention;

Figure 2 is a side elevation of the same;

Figure 3 is a top plan view of the name plate supporting bracket shown in Figures 1 and 2;

Figure 4 is a fragmentary part sectional elevation indicating the manner of attaching the bracket to one type of lamp post;

Figure 5 is a view in elevation of a bracket similar to that shown in Figure 3 with the detachable name plates omitted, the name being shown applied directly to the bracket;

Figure 6 is a view in elevation showing a modified form of street sign attached to a different type of lamp post than that shown in Figure 1;

Figure 7 is a sectional plan taken on line 7^a—7^a of Figure 6;

Figure 8 is a sectional elevation taken on line 8^a—8^a of Figure 6;

Figure 9 is a view in elevation in which the display sign shown in Figure 6 is reversed

and applied to a modified type of lamp post; 85 and

Figure 10 is a sectional elevation taken on line 10^a—10^a of Figure 9.

Similar reference numerals throughout the several views indicate the same parts. 60

The invention disclosed herein embodies an improved street indicating device for quick and easy attachment to different types of lamp posts and is constructed so that the name plates or brackets upon which the 65 names are disposed are inclined with respect to the axis of the post or to the axis of the lamp socket in order to afford better illumination of the names or signs, which may be disposed either above or below the light. 70

Referring to the drawings, 10 represents a lamp post upon which is superimposed a support including a base 11 having upwardly projecting curved arms 12 extending inwardly at their upper ends and connected by an annular ring or band 13 into which projects and to which is suitably secured the upper end of a bell-shaped reflector 14 preferably made of porcelain or like material. 75

A cap 15 serves as a cover for the annular member 13. The reflector 14 is made hollow and provided with a lamp socket not shown into which is screwed an electric lamp 16.

The wires or circuit connections, not shown, which lead to the lamp socket, are preferably carried upwardly through the lamp post and through the hollow arms 12 into the annular member 13 and downwardly to the reflector. The base portion 11 of the 80 lamp support is preferably tapered at two sides as indicated at 17 in Figure 2. The lower ends of the arms 12 are preferably cast integral with said tapered portion and are provided with annular enlargements 18 adjacent the base portion for a purpose which will appear hereinafter. The name plates 19 are carried by a lower bracket

which preferably embodies a central portion 85 20 having depending inclined sides 21 adapted to overlie the inclined faces 17 of the base portion 11, being in substantially parallel relation thereto as shown in Figure 2. The

name plates which may either be cast or formed of sheet metal are preferably secured 90 to the inclined sides 21 of the lower bracket by suitable bolts as indicated at 22, four or

which are shown, two at the upper and two 95

100

105

110

at the lower edge of the name plate. The central portion 20 of the lower bracket is provided with upwardly struck curved end portions 23 adapted to lie upon and to conform generally to the curvature of the lower ends of the arms 12 or the upper end of the base portion 11 where the arms merge with the latter. The portions 23 are formed by first slitting the metal for a short distance inwardly from the ends of the central portion 20 at the sides thereof, after which said portions are given the desired curvature with a suitable forming tool and bent upwardly to the correct angle. The lower bracket is easily applied between the arms of the lamp post by moving it downwardly to the position shown in Figure 4 at which time the portions 23, which are yieldable to a certain extent, are forced downwardly past the curved ends or abutments 24 of the angular enlargements 18 and sprung into engagement with the lower extremities of said portions whereby the bracket is firmly held in service position. Release of the bracket may be effected by prying it upwardly at one end with a suitable tool inserted under one side of one of the yieldable upstanding members 23.

It will be understood that the shape or form of the abutments 24 which receive the ends of the yieldable upstanding portions 23 may be varied as desired. This method of retaining the bracket in rigid position upon the lamp post makes it unnecessary to use bolts or other fastening means for attaching it to the post.

Extending transversely of the lower bracket and superimposed thereon is an upper bracket 25 having inclined sides as shown in Figure 4, said upper bracket being preferably constructed of sheet metal, the sides thereof terminating in relatively long and short angular base portions 26 and 27, respectively. These portions form a support for the bracket proper, the portion 26 being adapted to rest upon the horizontal portion 20 of the lower bracket and the portion 27 being disposed upon the outer extremity of the portion 26 as shown in Figure 4. The upper bracket 25 is connected with the lower bracket by a pivot bolt 28, which permits it to swing to different angular positions so that it may be adjusted from a normal right angle position with respect to the lower bracket to a different angle, depending upon the angle of intersection of the streets where the sign is placed. The upper bracket is adapted to be held in the desired position of adjustment by a clamping bolt 29 extending through the portion 20 of the lower bracket and through an arcuate slot 30 formed in the base portions 26 and 27 of the upper bracket. The base portion 26 is preferably of the length and shape indicated by dotted lines in Figure 3 and the base por-

tion 27 is preferably made relatively narrow so that it will not project any appreciable distance beyond the portion 20 of the lower bracket to cast a shadow over the lower name plates when the upper bracket is swung to its extreme angular position of adjustment.

The upper name plates 31 are placed on the opposite sides of the bracket 25 and have their lower edges secured thereto preferably by bolts 32 extending through holes 33 formed in the sides of the upper bracket at the lower edges thereof as shown in Figure 3. The name plates 31 are connected at their upper edges by bolts 34 which are disposed above the upper bracket and which serve to clamp the name plates thereon.

In the arrangement shown in Figure 5 the upper and lower brackets are the same as shown in Figures 1 to 4, inclusive, except that the holes for the bolts 22 and 23 are omitted, the names of the streets being painted or otherwise formed directly upon the inclined sides of the brackets rather than upon separate name plates applied thereto. With both brackets having their sides or name plates inclined with respect to the axis of the lamp 16 as shown, it can be readily seen that a single lamp employed for lighting the street corners will effectively illuminate the names of the intersecting streets so that they can be easily read by motorists or pedestrians approaching the same.

A particular advantage of the present device is that the entire sign may be quickly applied or removed as a unit from the lamp post without the use of screws, bolts or other fastening means whereby a considerable saving in the expense of applying the signs is afforded by greatly reducing the time required to place them in service. If preferred the combined brackets may be applied in advance of the name plates as the latter may be constructed independently of the former and easily attached thereto without removing or changing the position of the same.

In the modification shown in Figures 6 to 8 inclusive the lamp post indicated at 35 is provided with a globe 36 in which is disposed a lamp not shown, the wires or connections for which are extended upwardly through the post in the usual manner. A cap 37 is superimposed upon the globe and carries a short upstanding cylindrical portion 38 which is provided with an ornamental top 39 as shown in Figure 6. In this form of lamp post the street indicating sign is connected to the cylindrical portion 38 in a manner best shown in Figure 7 in which a bar of any desired shape is used, preferably a flat bar formed of strap iron and bent to provide a central band-like portion 40 arranged to extend substantially three-quarters of the distance around the cylindrical extension 38 of the cap 37 as shown in Figure 7.

The band-like portion 40 carries angularly disposed portions 41 and 42 which project at a right angle to each other and which are connected by a strap 43 through the use of bolts 44, the bolts being drawn up tightly to clamp the strap and band upon the cylindrical member 38, whereby the parts are firmly held in any desired position of adjustment. The vertical portions 41 and 42 are bent to provide horizontally extending arms 45 and 46 respectively as shown in Figure 7. Connected with the arms 45 and 46 are similarly constructed name plates 47 and 48, respectively. The name plates are preferably constructed of thin sheet metal with their sides inclined at a suitable angle to form V-shaped brackets as shown. The name plates 47 and 48 may be connected with the arms 45 and 46 in any suitable manner, but are preferably secured thereto by screws 49 as shown in Figure 8. The strap iron used in the construction of the arms and the band-like portion 40 is preferably of relatively thin material whereby the arms may be bent to extend at the desired angle with respect to each other to agree with the angle of the intersecting streets or highways on which the signs are used.

In the modification shown in Figures 9 and 10 the sign is substantially the same as shown in Figures 6 to 8 inclusive but is in reverse position for the reason that it is placed below the light. In this case the lamp post 50 is somewhat similar to the lamp post 35 but carries an extended cylindrical portion 51 on which an inverted globe 52 is mounted for housing the lamp not shown. The cylindrical portion 51 is shown somewhat larger than the corresponding portion 38 shown in Figures 6 and 7 and it will be understood therefore that the bandlike portion 40 will be correspondingly enlarged or made to conform to the size or shape of the part to which it is connected.

The names of the streets while not shown on the name plates 47 and 48 may be applied thereto in any desired manner, preferably by painting them on, but if preferred separate name plates may be bolted to the V-shaped plates 47 and 48 in the same manner as shown in Figures 1 and 2.

In each of the three different applications of the invention shown the name plates are angularly disposed and adjustably mounted with respect to each other and the opposite plates bearing the same names are inclined with respect to each other and to the axis of the lamp post or lamp socket so as to be more effectively illuminated than when disposed in a vertical plane in the usual manner. Furthermore, by inclining the name plates as described, a single lamp will provide the necessary illumination for the signs though more than one lamp may be used if desired.

What I claim as my invention is:—

1. In combination, a lamp post having oppositely extending arms projecting upwardly and connected at their upper ends, an electric lamp disposed between said arms, a reflector for directing the rays of light from the lamp downwardly between said arms, and oppositely inclined name holding plates disposed beneath the lamp between the arms in position to be illuminated by the lamp. 75

2. In combination, a lamp post provided with a lamp and having spaced abutments beneath the lamp, and a bracket connected by a horizontally disposed intermediate portion, the ends of which lie between the abutments in frictional engagement therewith having oppositely disposed name holding portions. 80

3. A street indicating device for attachment to a lamp support comprising a bracket including a central portion provided with outwardly extending inclined name holding portions said central portion having angularly disposed end portions for connecting the bracket with said support. 85

4. A street indicating device for attachment to a lamp support having spaced abutments thereon, comprising a bracket including a central portion provided with oppositely arranged inclined name holding portions, said central portion including angularly disposed securing portions adapted to engage said abutments in a manner to hold the bracket upon the support. 90

5. A street indicating device for attachment to a lamp support having spaced abutments thereon, comprising a bracket including a central portion provided with oppositely disposed name holding plates, said central portion having yieldable spaced portions at its ends inclined relative to the central portion and adapted to frictionally engage said abutments whereby to hold the bracket upon the support. 100

6. A street indicating device for attachment to a support, comprising a bracket having a central portion from the opposite sides of which project outwardly inclined spaced portions forming with the central portion a saddle shaped member adapted to straddle the support, and a name plate detachably connected with each of the inclined portions. 115

7. A street indicating device for attachment to a post, comprising a pair of angularly disposed connected name plates for intersecting streets, one of said plates being superimposed upon the other and each being adapted to extend in a plane inclined to the axis of the post. 120

8. A street indicating device adapted for attachment to a lamp post, comprising upper and lower name plates for intersecting streets, the lower plate including a central portion and outwardly inclined side 130

portions and the upper name plate being superimposed upon said central portion and adjustable to different angular positions with respect to the lower plate.

- 5 9. A street indicating device adapted for attachment to a lamp post comprising upper and lower brackets, the latter having a central portion provided with downwardly extending name holding portions and the former being superimposed upon said central portion and including oppositely inclined name holding portions extending transversely of the lower bracket.

10 10. A street indicating device adapted for attachment to a lamp post, comprising upper and lower brackets, the latter having a central portion provided with downwardly turned name holding plates and the former including oppositely inclined name holding plates extending transversely of the lower bracket, one of the last mentioned name holding plates having an angularly disposed base pivoted on the central portion of the lower bracket to permit the upper bracket to swing upon the lower and means for locking the upper bracket in different positions of adjustment.

11. In combination, a lamp post having a lamp thereon, a pair of angularly disposed connected name plates upon the post, one of said plates being superimposed upon the other and each being disposed in a plane inclined to the axis of the post and arranged to be illuminated by the lamp.

35 12. In combination, a lamp post having a lamp thereon, a pair of connected angularly disposed street signs carried by the post, one above the other and each including oppositely arranged name plates, one plate of each sign being disposed in a plane inclined to the axis of the post.

45 13. In combination, a lamp post, an offset arm extending upwardly therefrom and projecting inwardly at its upper end to a point substantially in alignment with the post, a lamp upon the inwardly projecting end of said arm and a street indicating sign connected with the post beneath the lamp and extending above the upper end of the post in position to be illuminated by the lamp.

50 14. In combination, a lamp post, an offset arm extending upwardly therefrom and having an inturned portion extending transversely of the axis of the post, a lamp depending from said transversely extending arm portion and a street indicating sign connected with and extending above the up-

per end of the post beneath the lamp and comprising oppositely inclined sign bearing portions.

60 15. In combination, a lamp support, a street indicating device upon the support comprising angularly disposed brackets one superimposed upon the other and each including a name holding plate inclined to the vertical and means connecting the brackets.

65 16. In combination, a lamp support, a street indicating device upon the support comprising upper and lower angularly disposed brackets the latter having a central portion upon which the upper bracket is disposed and a pair of name holding plates supported by each bracket, each of the plates being inclined to the vertical.

70 17. In combination, a lamp support, a street indicating device carried by the support comprising upper and lower angularly disposed brackets said lower bracket having downwardly extending name holding portions inclined to the vertical and said upper bracket being secured upon the lower bracket and including name holding portions inclined to the vertical.

75 18. In combination, a lamp support, a street indicating device carried by the support comprising upper and lower angularly disposed brackets, each bracket having oppositely disposed name holding portions inclined to the vertical the upper bracket having a base portion engaging the lower bracket and means connecting said base portion with the lower bracket.

80 19. A street indicating device adapted for attachment to a lamp post comprising upper and lower angularly disposed signs, the former being superimposed upon the latter, said signs each including a name holding plate and said plates being disposed in planes inclined to the vertical when the signs are disposed in service position upon the post.

85 20. In combination, a lamp post, a base member superimposed upon the upper end thereof and having an arm extending upwardly therefrom, said base member having oppositely inclined converging faces, a lamp supported by the arm, a pair of name holding plates connected with said base member and overlying said faces substantially in parallel relation therewith, and a reflector carried by the arm and adapted to reflect the rays of the lamp downwardly upon the name holding plates.

GEORGE S. SEARLE
